UNITED STATES PATENT OFFICE.

NELSON W. DALTON, OF BUFFALO, NEW YORK, ASSIGNOR TO CURTISS AEROPLANE AND MOTOR CORPORATION, A CORPORATION OF NEW YORK.

AEROPLANE-MOTOR SUPPORT.

1,246,022.

Specification of Letters Patent.

Patented Nov. 6, 1917.

Application filed April 16, 1917. Serial No. 162,529.

To all whom it may concern:

Be it known that I, NELSON W. DALTON, a citizen of the United States, residing at Buffalo, in the county of Erie and State of New York, have invented certain new and useful Improvements in Aeroplane-Motor Supports, of which the following is a specification.

My invention relates to aeroplanes and 10 more particularly to improvements in engine supports of the "between surface" or exterior type. The invention is characterized principally by the support of the engine bed beams at their forward ends by a 15 pyramidal structure of struts having its apex situated on a beam of a supporting plane. The advantage of this arrangement is that it produces the greatest strength of support beneath the greatest mass of the 20 motor.

Other features of the invention are the interbracing of the motors of a twin-motor craft and the rear end construction and formation of the engine bed beams.

25 Of the drawings:

Figure 1 is a side elevation of a tractor machine equipped with twin motors and with the motor supports, etc., of this invention;

30 Fig. 2 is a front end elevation of the machine illustrated in Fig. 1;

Fig. 3 is a top plan view (the upper supporting plane having been removed), and

35 Fig. 4 is a fragmentary perspective view detailing the motor support and engine bed formation.

Although the invention is designed for use in connection with a twin motored tractor machine, its use in connection with a 40 pusher machine is entirely practical.

In the embodiment of the invention selected for illustration, 10 designates the fuselage, 11-11 the twin motors, 12 the landing gear and 13-14 the upper and 45 lower supporting surfaces respectively. The motor or power units, it will be noted, are symmetrically disposed at opposite sides of the fore and aft axis of the craft, intermediate the surfaces 13 and 14, preferably 50 in the vertical planes of the terminals of the engine section panels.

Braces 15, V-arranged horizontally, extend out right and left from the fuselage 10, the apices of the respective braces lying

adjacent. These braces interconnect the fuselage and motors, the terminals of the braces constituting each V-brace engaging the inner beams of the engine beds at points in the vicinity of the fastenings for the inside struts of the pyramidal structures herein described.

The wing beams of the lower supporting plane are designated respectively 16 and 17, the corresponding beams of the superposed surfaces being unaligned vertically by reason of the stagger given said planes. This arrangement or stagger necessitates a forward disposition of the motors 11. Unlike the engine bed beams ordinarily used, the engine bed beams 18 here shown do not extend parallel throughout. At their rear ends the beams 18 converge so as to terminally engage the rear wing post 19 at a point intermediate its ends. A lap joint fitting 20, with the wing post 19 as its foundation, is utilized as the fastening means. The rearward convergence of the beams 18 decreases the head resistance by reason of the better streamline form of engine beds obtained.

The engine bed beams extend forwardly 80 beyond the vertical plane of the leading edge of the foremost wing. In this way ample clearance is provided between the plane of revolution of the propellers and the plane of the foremost wing. As a support for the beams 18 at their forward ends 85 the pyramidal structures 21 are provided.

These structures preferably consist of four or more struts arranged symmetrically about a line extending vertically from the 90 forward wing beam of the lower wing to the corresponding wing beam of the upper wing. The struts of each pyramid are commonly supported upon the forward wing beam of the lower wing and the apices of 95 the pyramids are situated preferably directly beneath the centers of mass of the respective motors. Greater strength and an equal distribution of the weight mass upon the several struts is in this way obtained 100 without dissymmetrically arranging the pyramid struts or angularly extending the pyramidal structures when considered as an entirety. The motors 11, the pyramidal structures 21 and the center struts 22 together 105 constitute separate wing post frames in which the center strut of each wing post frame is founded upon the motor casing

(see Fig. 1). Single center struts for each wing post frame are preferred, although not essential.

The motors being projected forward a considerable distance to clear the propellers of the staggered planes, and the engine bed beams 18 correspondingly forwardly extended, obviously some additional supporting means, such as the pyramidal structures 5 must be provided. These structures, it will be noted, lie symmetrically beneath the centers of mass of the motors and being founded on the forward wing beams of the lower wings, cause said wing beams to sustain 10 the principal weight masses of the machine. The motors, under no circumstances, are to be extended forwardly beyond the vertical 15 plane of the forward wing beams. To do this would necessitate that the center struts 20 22 continue beyond the plane of the top of the motor casing for foundation upon cross struts interconnecting the engine bed beams.

No limitation is intended to be made herein to the arrangement of the motor units 25 with respect to the fuselage or to the number of motor units or number of fuselages provided. What is intended to be covered is the mounting of a power unit intermediate 30 the supporting surfaces and in the plane of the forward wing beams thereof whereby it may be supported as disclosed through the medium of a pyramidal support having its apex founded upon one of the wing beams 35 of the lower supporting plane.

35 What is claimed is:

1. In an aeroplane, a fuselage, supporting surfaces arranged to extend intermediately across the fuselage, wing beams founding the supporting surfaces, a power 40 unit mounted intermediate the supporting surfaces in the vertical plane of the forward wing beams, and a pyramidal support for the motor unit having its apex founded upon one of the wing beams of the lower 45 supporting surfaces.

2. In an aeroplane, a fuselage, supporting surfaces arranged to extend intermediately across the fuselage, wing beams founding the supporting surfaces, a motor unit 50 ranged to longitudinally intersect the verti-

cal plane of the forward wing beams of the supporting surfaces, and a support for the motor unit comprising a plurality of upwardly diverging struts commonly fastened to the forward wing beam of the lower supporting surface. 55

3. In an aeroplane, a fuselage, supporting surfaces arranged to extend intermediately across the fuselage, wing beams founding the supporting surfaces, a motor unit 60 mounted intermediate the supporting surfaces, a pyramidal support for the motor unit having its apex founded upon one of the wing beams of the lower supporting surfaces, and means erected upon said motor 65 unit to vertically continue said support, to the corresponding wing beam of the upper supporting surface.

4. In an aeroplane, a fuselage, supporting surfaces arranged to extend intermediately 70 across the fuselage, wing beams founding the supporting surfaces, a motor unit arranged to longitudinally intersect the vertical plane of the corresponding wing beams of said surfaces, and a pyramidal support 75 for the motor unit comprising a plurality of upwardly diverging struts, said pyramidal support having its apex founded upon one of the wing beams of the lower supporting surface approximately below the 80 center of motor mass.

5. In an aeroplane, a fuselage, supporting surfaces arranged to extend intermediately across the fuselage, power units arranged 85 symmetrically at opposite sides of the fuselage, and substantially horizontally extending V-braces interconnecting the motor units and said fuselage.

6. In an aeroplane, a fuselage, supporting surfaces arranged to extend intermediately 90 across the fuselage, wing posts interconnecting said surfaces, engine bed beams arranged intermediate said surfaces, the beams at one end converging for securement to said wing posts intermediate its ends, and a 95 lap joint fitting constituting said securing means.

In testimony whereof I hereunto affix my signature.

NELSON W. DALTON.
